UNITED STATES PATENT OFFICE.

FLOYD F. HENRIOT, OF NEAR WINLOCK, WASHINGTON.

AUTOMATIC CONTROL FOR CARBURETORS.

Application filed August 10, 1922. Serial No. 580,928.

This invention relates to devices for automatically adjusting a carburetor of an automobile, or other similar engine, and has for its object the regulation of the needle valve 5 of the carburetor so that the flow of gasoline therethrough will be increased when the engine is cold and will become normal when the engine has been running long enough to be heated to its normal running temperature, thus permitting the easy starting of the engine without interfering with its economy when in full operation. Other objects are to provide such a device which is simple and cheap to make and easy to install.

15 I attain these and other objects by the devices and arrangements illustrated in the accompanying drawings, in which:—

Fig. 1 is a view showing my device mounted on an engine and showing a portion of the exhaust and intake systems thereof; Fig. 2 is a side elevation of the controlling thermostat; Fig. 3 is a section of a part of the carburetor showing the needle valve rod; and Fig. 4 is a cross section of the exhaust manifold showing the thermostat clamped thereto.

Similar numerals of reference refer to similar parts throughout the several views.

When an engine is cold it requires a richer mixture of gasoline in the intake air than it does for economical operation when it has reached its normal operating temperature. Therefore an automatic mechanism will have to open up the needle valve, which controls the amount of gasoline admitted to the carburetor, when the engine is cold and then partially close it again as it heats up. However, the extent of such opening of the needle valve should be very small and when my apparatus closes it down again it should bring it only to the adjustment at which the engine operates most economically. In the drawings I have very greatly exaggerated the motion of the needle valve, caused by my apparatus but it is to be understood that this is done for the purpose of clearness, since the motion is actually about one sixty-fourth of an inch and therefore would not be distinguishable in the drawings.

50 Referring now to the drawings, the carburetor 1 is shown as connected to the intake pipe 2 leading to the manifold 3 of the engine in the usual manner. The carburetor has a cap 4 secured to its upper side and a screw-threaded hole passes therethrough as usual. A manually operated adjusting

sleeve 5 screws in the hole in the cap 4 and enters the interior of the carburetor. This sleeve 5 is turned by the flange 6 thereon and is locked in any adjusted position by 60 the lock nut 7 screwing on its shank and engaging the top surface of the cap 4. The sleeve 5 has a central hole through it.

The needle valve 8 is formed on the end of a long rod 9 and controls the gasoline 65 passage 10 in the carburetor 1, opening said passage as it is raised therefrom. A collar 11 is secured to the rod 9 below the lower end of the sleeve 5 and is adapted to limit the upward motion of the rod in the sleeve 70 and thus limit the extent to which the apparatus may open up the passage 10 when the engine is cold. A similar collar 12 is secured to the rod 9 immediately above the upper end of the sleeve 5 and is adapted to 75 limit the downward movement of the rod in the sleeve thus closing the passage 10 to the extent permitted by the adjustment of the sleeve 5, it being intended that when the rod 9 is lowered the needle valve 8 will be 80 in the desired position for the continued running of the particular engine, and this point is adjusted by turning the sleeve 5 in the cap 4.

A thermostat 13 is formed of a strip of 85 brass 14 riveted at various points to the upper side of a similar strip of iron 15. One end of this thermostat 13 is riveted to a cross bar 16. The thermostat 13 is clamped between the cross bar 16 and the exhaust 90 manifold 17 of the engine by a U-bolt 18, which encircles the lower part of the manifold and which passes through holes in the ends of the cross bar 16. Suitable nuts are 95 screwed on the ends of the U-bolt and bear against the upper surface of the cross bar 16.

This thermostat 13 extends to a point directly over the carburetor 1, and has a slot in its free end. The rod 9 is screw-threaded at its upper end and this part 100 passes through the slot in the free end of the said thermostat 13. The rod 9 is adjustably secured to the free end of the thermostat 13 by being clamped between the lower and upper nuts 19 and 20, respectively, screwed 105 on it and this adjustment is secured from being inadvertently changed by a lock nut 21 engaging the said nut 20.

My device operates in the following manner:—The coefficient of expansion of brass 110 being greater than that of iron, it follows that for a given change in temperature the

brass will change its length more than the iron does and therefore, since the two strips 14 and 15 are riveted together at various places, the thermostat formed by them changes its curvature with changes in its temperature. But one end of this thermostat is held fast to the exhaust manifold 17 by the clamp and therefore the free end tends to rise as the temperature of the thermostat falls and to press downward as the temperature rises. This action is communicated to the rod 9 fastened to it, and therefore when the engine is cold the thermostat pulls the rod 9 upward until the lower collar 11 engages the lower end of the sleeve 5, thus opening the passage 10 in the carburetor a definite amount depending on the free motion of the rod 9 permitted by the two fixed collars 11 and 12 and increasing the supply of gasoline when the engine is started (under this condition the rod 9 is in tension and holds the thermostat from further motion upward); while, as the exhaust manifold 17 becomes heated by the high temperature of the exhaust gases, it gradually heats the thermostat 13 and reduces the upward pull on the rod 9; then, when the temperature of the thermostat has become high enough, the end of the lever 30 actually presses down on the rod 9 moving it downward until the collar 12 engages the upper side of the sleeve 5, thus closing the passage 10 to the normal operating position. In this condition the rod 9 is in compression and holds the thermostat from further motion downward. It should be noted that the allowed motion of the rod and of the end of the thermostat is much smaller than the motion of the thermostat would be if it were free from the rod; therefore the said thermostat, in being confined to such limited motion, is actually absorbing some of the motion which it otherwise would make. This is purposely provided in order to give an appreciable time after the engine is started before the valve is closed to normal and to cause sufficient delay after the engine is stopped, or the gasoline is shut off, before the valve opens up. This prevents the control being too sensitive and makes it open the needle valve only after the engine has been standing long enough to cool off, and also gives the engine time to warm up effectively before closing the valve to its normal operating position.

There are several ways in which this ap-

paratus could be changed without altering the essential ideas therein; for instance, other metals than brass and iron might be used, the essential point being that they have different coefficients of expansion, also the means of attaching the thermostat to the exhaust manifold may be altered, also a single collar on the rod may be substituted for the two collars described if it operates between two suitable stops on the sleeve, also the means of attaching the rod to the thermostat may be changed.

Having described my invention, what I claim is:-

In a device of the class described, the combination with an exhaust manifold; a carburetor; a gasoline passage therein and provided with a valve seat; a screw sleeve mounted in and passing through the shell of the carburetor, coaxial with the valve seat, and rotatable in the shell, thereby providing positive adjustment therein relatively to the said valve seat; a needle valve, adjacent to but separated from said valve seat, having a stem extending coaxially through the sleeve, said valve coating with the valve seat whereby the extent of opening of the gasoline passage is controlled by the adjustment of said needle valve closer to or further from said seat; two limiting collars on said valve stem, one on each side of said screw sleeve and closely adjacent thereto, whereby free but limited axial movement of the valve stem is permitted relative to the adjusted position of the sleeve but all other axial motion of the stem is prevented, and whereby the normal opening of said needle valve is controlled by the adjustment of said screw sleeve in the carburetor shell; and a thermostat fixedly mounted at one end to the exhaust manifold whereby it is heated, its free end being secured to the outer end of the valve stem, said thermostat being positively stopped from motion in either direction, under the influence of the heating or cooling manifold, by the positive engagement of one or the other of said limiting collars with the adjusted screw sleeve, whereby the needle valve is slightly opened beyond its normal adjusted position when the manifold is cool and remains fixed at said extreme open position until the manifold has been heated an appreciable time, and is then closed thereby to said normal adjusted position.

FLOYD F. HENRIOT,
